UNITED STATES PATENT OFFICE

2,525,709

REFRIGERATED DRINKING FOUNTAIN

Samuel O. Morrison, Media, Pa., assignor to
Sunroc Refrigeration Company, Dover, Del., a
corporation of Delaware

Application December 3, 1947, Serial No. 739,475

7 Claims. (Cl. 62—141)

1

My invention relates to refrigeration devices, particularly of the type of water coolers and refrigerators.

A purpose of my invention is to cleanse the air which is introduced into a refrigeration space through a filter, and preferably to cleanse the filter by a water drip.

A further purpose is to provide an air connection for introduction of displacing air to displace liquid in a liquid dispenser, and to interpose a filter in the connection.

A further purpose is to draw air into a water storage and cooling space to replace the water dispensed by an inlet through a filter preferably cleansed by water drip and extending to a point preferably adjacent the top of the water space.

A further purpose is to provide air inlet to a food storage space through a filter preferably cleansed by water drip.

A further purpose is to provide a filter and water drip cleanser on a dispensing faucet, and to draw air into a refrigeration space from the interior of the faucet beyond the filter.

Further purposes appear in the specification and in the claims.

In the drawings I have chosen to illustrate a few only of the numerous embodiments in which my invention might appear, choosing the forms shown from the standpoints of convenience in illustration, satisfactory operation and clear demonstration of the principles involved.

Figure 1 is a front elevation of a combined water cooler and refrigerator to which my invention has been applied.

Figure 2 is a front elevation of a bottle water cooler to which my invention has been applied.

Figure 3 is a longitudinal section of a dispensing faucet modified in accordance with the invention.

Figure 4 is a fragmentary vertical section showing a filter adjoining the water cooling compartment.

Describing in illustration but not in limitation and referring to the drawings:

In water coolers or drinking fountains of the character which employ a closed dispensing receptacle containing a predetermined body of water to be dispensed, whether it be a water storage compartment entirely contained within the cooler or a water storage compartment having a water bottle to supply the water and add to its capacity, the dispensing operation inevitably involves displacement of water by air. Likewise in dispensing other liquids occasions arise when replacement air must be supplied. In the prior art

practice air has frequently entered from the interior of the water cooler. Such air has, of course, been contaminated by dust, fumes, oil vapors, and the like, incident to the operation of the mechanical refrigeration unit, including the fan, where employed. Also replacement air is frequently drawn from the surroundings in locations such as industrial plants which are inherently dusty or which present certain industrial hazards by reason of the composition of the dust. This has frequently led to complaint about the taste of the water which has heretofore been very difficult to explain or correct, since the source of the difficulty has not previously been recognized.

Likewise in refrigerator spaces, such as food storage compartments, deep freeze units, ice freezing compartments, and the like, the operating conditions, opening and closing of the doors, changes in prevailing temperature, or the like, may cause air to be drawn in and this again has sometimes resulted in drawing in air contaminated with dust, fume or vapor, either from the mechanical refrigeration unit or from the adjoining room.

I have developed mechanism to minimize or overcome this difficulty.

Figure 1 illustrates a water cooler of the character employed in a copending patent application of Orville C. Morrison, Samuel O. Morrison, John G. Wehrwein, and Earl Gott, Serial No. 6,924, filed February 7, 1948, for Refrigerator and Water Cooler.

This device has been modified to apply the mechanism of the present invention, as shown more in detail in Figure 3.

The water cooler cabinet 20 is of generally rectangular form, and has a top 21, front 22 and sides 23, as well as a back not shown.

40 A removable lid 24 permits access into a water storage and cooling compartment 25 which extends the length of one side of the top of the water cooler cabinet as shown, and is separated by a partition 26 from a refrigerator compartment 27 on the opposite side. A water cooling unit 28 of a mechanical refrigeration unit whose motor-compressor (hermetic unit) is shown at 29, is in heat transfer relation with the water of the water storage and cooling chamber. Likewise a cooling unit 30 of the same mechanical refrigeration unit and suitably connected in series with the unit 28 is placed in the refrigerator compartment. The remaining components of the system may be of any suitable character as well known. 55 The water cooling space and the refrigeration

space are suitably insulated at all outer walls at 31.

The upper portions of the water cooling and refrigeration spaces are suitably provided with sterile lamps 32 and 33 for the purpose of germicidal action.

Water is dispensed from the water storage and cooling space through a dispenser 34, here shown as a faucet, which is preferably located relatively high with respect to the water storage and cooling space and connected thereto by a pipe 35 which extends downward, thus assuring that a substantial amount of water will remain at all times in the space to aid in cooling added water. The dispenser is provided with the usual operating handle 36 or any other suitable operating means for controlling the faucet valve 37. The discharge opening 38 is suitably covered by a housing 39 which contains a filter 40, preferably in the form of a plurality of metallic screens, which will preferably be of silver, silver plated, or the like, for germicidal action, or other suitable material. The housing is held in place by threads 41 and is flanged over at 42 to retain the filter.

Inlet air to the water storage and cooling compartment and to the refrigerator is brought in through a connection 43 beyond the filter, so that all air entering the connection will be filtered. The connection 43 is carried through the wall of the faucet at 44 and is branched at 45 to provide one pipe 46 extending into the refrigerator and another pipe 47 which extends preferably to a point above the top of the water 48 in the water storage and cooling space.

In the preferred form the filter is washed and this is preferably accomplished by a drip valve 49 which controls a drip port 50 to allow a minute drip from the faucet down through the filter 40 and out the faucet. This drip keeps the filter clean and moist and improves the cleansing of air that is drawn in. The amount of drip can be adjusted by adjusting the valve 49 so that the drip is very minute and will not represent a serious waste of water.

As discussed in the copending application, any surplus water is caught in a catch basin 51 which drains through a pipe 52 into a waste water storage container 53 which discharges through a cock 54 preferably located adjoining a bottom recess 55 in the front of the cabinet. Any water in the refrigeration compartment may likewise be drained through a pipe 56 and a trap 57 into the container 53. In case it is necessary to drain the water storage compartment completely, this can be accomplished through a pipe 58 controlled by a valve 59.

The principles of the present invention may similarly be applied to the conventional type of bottle cooler shown in Figure 2, which is provided with a refrigeration unit as described, the cooling unit 60 of which is in heat transfer relation with a water storage and cooling compartment 61 on which is mounted a bottle 62 by a cushion ring 63. No inlet air slot in the cushion ring should be provided. The cooling unit receives refrigerant from the compressor after it has passed through a condenser 64 and a metering device 65 (expansion valve or constrictor) and returns the refrigerant to the opposite side of the compressor. In the form of Figure 2 the pipe 47 is preferably extending upwardly at 47' to a point near the top of the inside of the air space 66 above the neck of the bottle.

The connection to the air space at the top of

the water cooling compartment is preferably accomplished through a filter 67 located in the wall of the cooling compartment and having a filter medium 68 preferably consisting of a series of fine silver or other metallic filter screens. Thus in this case the air derives advantage by going through two filters in succession but it will be understood that either or both may be used.

It will be evident that air is admitted both to the refrigerator compartment and the water storage and cooling compartment whenever conditions require, as by pressure charge or dispensing of water, and the air thus introduced is cleansed and filtered, preferably by a filter which is itself cleansed by water drip.

In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

Having thus described my invention what I claim as new and desire to secure by Letters Patent is:

1. In a water cooler, a mechanical refrigeration unit including a cooling unit, a water storage receptacle in heat transfer relation to the cooling unit, a dispenser connected to the water storage receptacle, an air connection to the water storage connection to introduce air to replace the water dispensed, a filter at the inlet of the water storage connection to purify the inlet air and a conduit conveying a water drip over the filter to clean the same.

2. In a water cooler, a mechanical refrigeration unit including a cooling unit, a water storage receptacle in heat transfer relation to the cooling unit, a dispenser connected to the water storage receptacle, an air connection to the upper portion of the water storage receptacle to introduce air to replace the water dispensed, a filter for the inlet end of the air connection and a conduit conveying a water drip over the filter to clean the same.

3. In a refrigerator, a mechanical refrigeration unit including a cooling unit, a refrigerator compartment in heat transfer relation with the cooling unit, an air connection to the refrigerator compartment, a filter at the inlet of the air connection and a water drip over the filter to clean the same.

4. In a drinking fountain, a mechanical refrigeration unit including a cooling unit, a water storage and cooling space in heat transfer relation with the cooling unit, a dispenser faucet connected to the water storage space, a filter in the faucet and in the path of the water discharged therefrom and an air inlet from the water storage and cooling space to the space through the faucet and behind the filter.

5. In a drinking fountain, a mechanical refrigeration unit including a cooling unit, a water storage and cooling space in heat transfer relation with the cooling unit, a dispenser faucet connected to the water storage space, a filter in the faucet, an air inlet to the space through the faucet and behind the filter and a conduit having a water drip through the faucet and over the filter.

6. In a water cooler, a water cooling compartment having a liquid space and an air space thereabove, a mechanical refrigeration unit for cooling the liquid, a dispenser connected to the

liquid, an outside air connection to the air space, a filter in the outside air connection and a conduit having a liquid drip over the filter for washing the filter.

7. In a water cooler, a water cooling compartment having a liquid space and an air space thereabove, a mechanical refrigeration unit for cooling the liquid, a dispenser connected to the liquid, an outside air connection to the air space, a filter in the air connection, a conduit having a liquid drip over the filter for washing the filter, and a second filter in the air connection closer to the air space than the first filter.

SAMUEL O. MORRISON.
